UNITED STATES PATENT OFFICE

LUDWIG HENNINGER, OF DURLACH, GERMANY, ASSIGNOR TO BADISCHE MASCHINEN-FABRIK & EISENGIESSEREI VORMALS G. SEBOLD UND SEBOLD & NEFF, OF DURLACH, GERMANY

FOLDING TOOL FOR MATCH-BOX MAKING MACHINES

Application filed September 4, 1929, Serial No. 390,229, and in Germany June 16, 1928.

My invention relates to improvements in folding tools for match-box making machines, and more particularly for folding over or tucking in the edge of the paper of the inner boxes of match-boxes.

For the purpose of folding over the edge of the paper when winding the blanks of inner boxes for match-boxes from a strip of wood or cardboard with applied paper adhesive strips, two kinds of tucking or folding tools are employed. The winding mandrel around which the wall of the box is wound is provided with a groove extending completely around the mandrel. The edge of the paper projects beyond the groove and must be folded or tucked into the same. For this purpose either a roller with a projecting edge or flange is employed which contacts permanently with the winder, or a rocking or oscillating knife-like folding tool operated by a suitably designed cam is used.

The flanged rollers have inherent disadvantages in that reliable and efficient introduction of the edge of the paper into the winder groove is not ensured at all times, particularly at the winder corners. It has been attempted to prevent this by giving the flange a peculiar shape, but it was found that this endangers the entire edge of the paper.

My invention does not relate to a cylindrical folding tool, but to knife-shaped rocking folders.

Prior to my invention folders with straight folding edges were used. When the sides of the winding mandrel and of the wall of the box stood substantially vertical the folder quickly forced the paper into the groove of the mandrel. The in and out movement of the straight-edged folder must be short and sharp so that the folder may pass out of the way of the winder with sufficient certainty.

To ensure such rapid in and out motion of the folder it was necessary to provide very shallow recesses or slender curves on the circumference of the cam for actuating the folder and it was also necessary to run the machine slowly to enable the rollers contacting with the circumference of the cam and mounted on the folder lever to follow the shallow recesses as closely as possible. The slow speed

naturally reduced the output of the machine.

To perfect the folding or tucking operation it was also proposed to provide a second special plate with an angular edge to exert the permanent action which the folder proper is unable to effect. This second plate requires its own driving means and complicates the entire mechanism.

My invention obviates the disadvantages above pointed out by curving the folding or tucking edge of the folder in such a manner that such edge remains in engagement with the groove during substantially the entire time required by any one side of the mandrel to move along the folder and only a comparatively short recession of the folder is necessary at each corner of the mandrel. The shape of the cam for actuating the folder is so correlated to the shape of the folder edge that the latter moves substantially rectilinearly adjacent the base of the groove and thus effects perfect folding of the paper. By virtue of this correlation, the cam may be provided with substantially long curves which the cam roller can easily follow closely even at high operating speeds. The capacity of the machine is thus greatly increased and the quality of the work materially improved.

My improved mechanism is, furthermore, distinguished by its simplicity since a second supplementary tool with a special drive is not required.

An embodiment of my invention is illustrated in the accompanying drawings in which

Fig. 1 is a cross-section of the device,

Fig. 2 is a similar cross-section with the parts in different positions,

Fig. 3 is a side elevation, and

Fig. 4 shows the active part of the lift cam in natural size.

Referring to the drawings it will be seen that the folder *a* is mounted at the upper end of a lever *b* the lower end of which is secured to a stud shaft *c*. On this short shaft there is also mounted a lever *d* which at its free end carries a roller *e* adapted to revolve freely around the pin *f*. Within reach of the roller there is mounted a cam *g* on the

main-shaft h of the machine and a coil spring i exerts sufficient pull on the lever b to ensure a close contact of the roller e with the periphery of the cam g .

- 5   In front of the folder a there is mounted upon the shaft h the winding mandrel l which is adapted to be rotated from the main-shaft h by means of a pair of spur wheels indicated by their contacting pitch circles m ,
10   n . The direction of rotation of the cam g and of the winding or wrapping mandrel is indicated by arrows. The box may be held on the mandrel by any suitable means common to this art, as for example by rollers
15   which support the box, and the latter may be removed from the mandrel by any well known means such as stripping fingers moving lengthwise of the mandrel.

Fig. 1 of the drawings shows the roller e just about to leave the concentric or non-operative portion of the circumference of the cam and to enter the first relatively long recess or notch of the cam. The folding edge a^1 of the folder a is just beyond the corner 20 of the mandrel or box. Inasmuch as during the continuation of the rotation of the winding mandrel l the roller e gradually approaches the center of the cam or shaft h , owing to the curvature of its front edge the 25 folder a soon enters the groove of the winding mandrel.

The curvature of the edge a^1 , the shape or configuration of the cam g and the rotation of the winding or wrapping mandrel l are so 30 correlated that the folding edge a^1 remains at a short distance from the base or bottom of the groove of the winding mandrel and moves linearly in relation to the bottom of the groove thus folding the material.

40   When passing from one side of the mandrel to the other the folder a is moved outwards at a slightly higher speed, see Fig. 2, so that it is able to pass out of the way of the 45 corners of the mandrel or the box and to re-enter the groove shortly after the corner has passed.

In comparison with the abrupt curves used heretofore those of the cam herein shown are 50 very long so that smooth operation is attained even at very high speeds of the machine. Due to the fact that the paper is comparatively gently applied to the box the quality of the product is also considerably improved.

55   I claim as my invention:—

1. In a box forming machine comprising a grooved mandrel, a rocking knife-like folding member and a cam for continuously controlling said member, the folding edge of 60 said member being so curved and the cam faces of said cam being so shaped that the curved edge of the folder during the operation thereof forms a substantially straight line adjacent the base of the groove along 65 the sides of the mandrel and remains in said

groove for substantially the entire time required by any one side of the mandrel to move along the folder.

2. A box forming machine, as claimed in claim 1, in which further cam faces of the 70 said cam are so shaped that the curved edge of the folder during the operation thereof is moved outwardly from the groove at increased speed to pass out of the way of the corners of the mandrel and to reenter the 75 groove shortly after each corner has passed beyond the path of movement of the curved edge of the folder.

In testimony whereof I affix my signature.

LUDWIG HENNINGER.
